[57] ABSTRACT

The specification describes a swimming pool construction in which the earth retaining walls that form the pool sidewalls are specially constructed so that the earth adjacent to the sidewall remains substantially undisturbed. The construction uses aluminum panels having integral tubular sleeves extending vertically and spaced apart along the length of the panel. The boss of each panel is anchored into the earth supporting the wall by pins inserted through the sleeves from above and driven into the earth. This eliminates the need for "overexcavating" the pool site. The top of the panels are anchored into the ground with laterally extending braces.

SWIMMING POOL CONSTRUCTION

This invention relates to swimming pool construction.

BACKGROUND OF THE INVENTION

A persistent problem in the construction of "in-ground" swimming pools continues to be the instability of the earth around the periphery of the excavation. The building sequence typically involves overexcavating for the pool itself, then backfilling around the completed pool. Shifting and settling of the earth fill often disturbs the pool structure. Vinyl liner pools of the kind having an earth bottom can actually be flooded from surface water diverted as the result of overexcavation of the pool site. In such cases the vinyl liner may be shifted and the carefully leveled bottom may be disturbed.

In conventional practice the necessity for forming an excavation significantly larger than the pool itself is to accommodate the support structure for the sidewall. This typically comprises an "A" frame, or similar bracing device, which projects laterally from the region of the lower edge of the sidewall and then connects to a diagonal member affixed to the upper portion of the sidewall. Various other arrangements have been employed for supporting the sidewalls of the pool but these also typically involve bracing members extending laterally from the lower portion of the sidewall. It is this approach to sidewall support in the construction of most vinyl liner pools that makes it necessary to overexcavate the pool site. It is significant to note that this type of construction is almost always used for making aluminum or steel wall plastic liner pools.

BRIEF DESCRIPTION OF THE INVENTION

One aspect of this invention is to provide an improved wall structure for use in plastic liner pool construction.

A further aspect of the invention is to provide an improved sidewall structure for use in conjunction with rigid plastic shells of the kind described in United States Patent application Ser. No. 56,802, filed July 21, 1971, now U.S. Pat. No. 3,673,751 and assigned to the present assignee.

According to one aspect of the invention an improved wall construction that overcomes the necessity for overexcavating involves the provision of a sleeve member affixed to or made integral with the wall. An elongated anchor rod is then inserted through the sleeve and then is driven into the earth below the wall. This serves to anchor the lower portion of the wall against lateral movement without having structural members protruding laterally from the lower portion of the wall. The upper portion of the wall is anchored with lateral support members which can be installed without substantially disturbing the earth. As a consequence of this anchoring technique the required excavation need only be wide enough to accommodate the width of the sidewall. By thus allowing for undisturbed earth contiguous to the wall many of the disadvantages of the prior art wall structures are overcome.

DETAILED DESCRIPTION OF THE INVENTION

The above and other aspects of the invention will be more apparent from the following detailed description. In the drawing:

FIG. 1 is a sectional view through a pool wall panel and the excavation in which it is installed illustrating one embodiment of the invention;

FIG. 2 is a plan view of the wall section of FIG. 1;

FIG. 3 is a sectional view similar to that of FIG. 1 showing a preferred embodiment of the invention in which the wall construction of the invention is used in combination with a rigid plastic or fiberglass shell.

FIG. 4 is a sectional view showing in detail an exemplary fitting for interlocking panels to form the rigid shell shown in FIG. 3; and

FIG. 5 is a sectional view similar to that of FIG. 4 showing another interlocking panel arrangement.

Referring to FIG. 1 the sectional view is taken through a wall of an "in-ground" pool showing the technique for bracing the wall against lateral movement while retaining the earth contiguous to the wall in an undisturbed condition. The pool walls are typically formed of flat steel or aluminum panels that may have reinforcing ribs or other known structural features on the outside of the wall, with the inside of the wall generally smooth to accommodate the conventional pool liner. The bottom of the pool is typically earth or sand, smoothed to give an acceptably flat pool bottom. The panels are typically bolted together or interlock to give the length and width desired.

In FIG. 1, the wall panel 10 is shown resting on undisturbed earth 11. A hollow sleeve 12 extends vertically along the outside of the panel, firmly fixed thereto or integral therewith. In a preferred sense these sleeves are steel or aluminum and may be welded to metal panels. It may also be possible to extrude the wall and sleeves in one piece. A retaining pin, shown in phantom at 13, is inserted through the sleeve and driven into the earth 11. It will be appreciated that this pin, which anchors the wall against lateral movement of its lower end, can be installed from the surface surrounding the excavation, and that the volume of undisturbed earth, 16, can extend contiguous to the wall. The space shown between the wall and the earth 16 represents the most convenient minimum tolerance with which the excavation can be made while still accommodating the width of the wall. The average dimension for this spacing advantageously is less than half the vertical dimension of the wall panels.

The upper portion of the wall is anchored via brace 17, bolted at 18 to a rib section formed on the wall section 10 (see FIG. 2). The other end of brace 17 is anchored in concrete 19 with anchor rod 20.

Referring back to the wall member 10, it includes, in this particular embodiment, a mounting bracket 21 to which the pool coping 22 is attached. The coping 22 is shown here as including a longitudinally extending slot 23, into which a conventional vinyl pool liner 24 is inserted.

A plan view of the wall member, taken through section 2-2, appears in FIG. 2. The elements are designated as in FIG. 1. A significant feature that appears in this view is the sleeve 12 that is slotted throughout its length. This feature is optional, but is useful for obtaining tight engagement between the anchor rod and the sleeve without the necessity for very close dimensional tolerances.

The materials from which the foregoing elements of the wall assembly are fabricated will be largely a matter of choice. Steel is often used in swimming pool construction. Alternatively, the flat portion of the wall 10

can be wood, e.g. cypress. However, the preferred material for the wall structure described is aluminum, selected for its light weight, strength, and corrosion resistance. The light weight characteristic is especially important for this structure since this pool is designed largely for convenience and ease of installation. The only major equipment essential for its installation is that used in forming the excavation. The simplicity of the fabrication of the pool is a significant virtue in its design. In many cases unskilled workers and even homeowners will be able to complete the major portion of the construction.

Referring again to FIG. 1 the lateral brace 17 is shown as extending beneath the ground primarily for esthetic reasons. From FIG. 2 it is evident that a trench 25 must be provided as well as a hole for the subsurface anchor 19. The anchor is shown as concrete although the terminus of the brace 17 could be staked or pinned to the earth. Since the trench for the brace 17 can be quite thin and the distance between braces can be typically several feet, the earth 16 is not unduly disturbed even if the brace is anchored fairly deep into the ground. Mechanically, there is no apparent advantage in doing this although the options in installing the braces for the upper portion of the wall are undoubtedly many. For example, the brace need not extend laterally. If the normal terrain of the earth wall 16, where the brace would be anchored normally, is lower than the top of the wall then the brace may be anchored in the earth well below the top of the wall. However it will be evident that if the pool walls do not extend below the grade level at some point, by a distance of at least one half of the vertical wall dimension, then the value of preserving the earth wall 16 undisturbed is diminished to the point where other wall structures may be equally effective.

A preferred embodiment of the invention is shown in FIG. 3. This pool construction is essentially an improvement of the pool structure described and claimed in United States Patent application Ser. No. 56,802, filed July 21, 1971 and assigned to the present assignee. With reference to that application, and particularly to FIG. 3 thereof, a rigid pool shell is shown disposed within the plastic pool liner. This construction eliminates the need for a smooth earth floor, protects the pool liner from contact with pool users and from degrading ultraviolet radiation, and provides several other advantages described in said copending application. The structure described in that application includes an earth retaining wall, exterior with respect to the pool liner, to provide structural integrity for the pool excavation. A preferred earth retaining wall structure is that of the present invention.

The structure of FIG. 1 of this application provides an ideal sub-structure for the rigid shell of the aforementioned application and the combination can effectively be implemented by simply extending the top grid member 21 so as to provide a fitting for attaching the rigid interior shell. Such a structure is shown in FIG. 3. The redundant elements of FIG. 1 are shown in primed numbers. The significant modification is in the top grid member, indicated here at 31, which is affixed to or integral with the wall panel 10'. The grid member 31 extends beyond the wall and liner, and terminates in a fitting 32 which engages a rigid pool wall panel 34. The pool wall panel has a structure similar to that described in the aforementioned application which allows it to be

snapped into engagement with the fitting 32 in the suspending grid 31. The grid member 31, or alternatively the wall panel 10', is provided with a channel 33 in which the beaded liner 24' is inserted. Note that the pool coping 22' is identical to that used in the liner pool of FIG. 1, even though the structure of the grid to which it is affixed is quite different. This universal coping section can be installed by simply snapping it into engagement with the top grid of the wall panel.

10 The interlocking arrangement for the panels of the rigid shell is shown in FIGS. 4 and 5. This particular arrangement of the rigid panels and the interlocking fittings is given by way of example. The invention in its broader aspects encompasses any useful arrangement 15 of rigid panels that form a pool interior shell within the liner-retaining wall combination described previously.

20 The panel arrangement shown in FIG. 4 comprises a pool interior panel 41 which is ordinarily square or rectangular in dimension and terminates at both edges in a re-entrant channel 42, and a folded edge portion 43. This leaves an interior channel portion 44. The panel 41 and the counter panel 45 are glued or otherwise affixed to the filler 46. The filler can comprise a 25 series of rib members spaced apart, or could be any of a number of structural members of a variety of materials simply serving to support the panels in spaced relationship. Foamed plastics such as polyurethane can be used in combination with rigid plastic, wood or metal supports.

30 The panel 45 terminates at each edge with a channel 47 and a folded edge 48, the latter at least partly co-extensive with the edge 45 of the other panel. The channel 47 serves to engage the female fittings as will be described.

35 This type of panel member is adapted to be used with joining members, one of which is shown at 50, joining two floor panels 60 and 61. It will be recognized that this fitting functions the same as fitting 32 in the suspending grid member 31. The joining member 50 resembles an I-bar with one channel-forming member 51, somewhat longer than the other channel-forming member 52, although this feature is not per se essential. The edge fitting of the panel is adapted to engage 40 within the channel 53, formed by arms 51 and 52, and main beam member 54. The arm 51 terminates with lip 55, and this lip engages the notch 47 of the male fitting. Arm 52 terminates with lip 56, which engages the re-entrant channel 42 of the panel. The I-bar 50 is preferably rigid. Good results are obtained with aluminum extrusions.

45 It can be inferred from this figure that the combination of the male fitting of the panel and the I-bar joining member comprise an interlocking assembly that can be joined simply by snapping the members together, it being remembered that the edge portions of the panel are sufficiently resilient to allow the channels 42 and 47 to close together. The normal channel separation is such as to tightly engage the arms 51 and 52. The biased surfaces 57 and 58 ease the joining operation with this particular design. The additional length of arm 51 as compared with the length of arm 52 also contributes to this result. The panel is most effectively joined to a joining member by tilting the panel with respect to the joining member while engaging lip 56 and channel 42. Then by urging the members into horizontal alignment, the interlock is effected. The actual operation is ac-

complished with remarkably ease and the interlocking joint is very effective.

The sidewall to floor panel joining strips, shown schematically at 38 in FIG. 3, are angled if appropriate for forming the hopper of the pool. However, it will be apparent that the endwall to floor panels cannot be joined in the same way as two such joints cannot be interlocked at right angles to one another. An appropriate design for the endwall to sidewall joint and joining strip is shown in FIG. 5. In FIG. 5 the sidewall panel is shown at 70 and the joining strip at 71. These members are interlocked as before. However, the joining strip 71 is designed so that the floor panel 72 will engage directly without tilting the panel. The panel rests on support arm 73 and is retained with the aid of the nub 74. It may also be advantageous to bolt this panel to the fitting 71 or to provide a retaining pin, such as that shown at 75 engaging hole 76 formed through one side of the panel.

Referring back to FIG. 1, note that the pin 13 does not extend the length of sleeve 12. It is sufficient if only a few inches of the pin remain in the sleeve. It is preferable to have the pin shorter than the sleeve so that the sleeve can be used as a guide in driving the pin into the earth.

By welding the sleeves 12 to the panel 10 as described, a heavy gage sheet can be used and the interior surface of the sheet can be smooth to accommodate the pool liner. The alternative of folding the sheet to form a sleeve does not allow either of these expedients.

Various additional modifications and extensions of

this invention will occur to those skilled in the art. All such variations and deviations that basically rely on the teachings through which this invention has advanced the art are properly considered to be within the spirit and scope of this invention.

We claim:

1. A swimming pool construction comprising:
an earth excavation,
a retaining wall for retaining at least a portion of the side wall of the excavation,
and a water retaining liner affixed to the retaining wall and covering the major portion of the excavation,

the invention characterized in that the retaining wall comprises a plurality of aluminum wall panels disposed edge-to-edge and extending around at least a portion of the periphery of the excavation, each wall panel comprising a rigid sheet having a plurality of elongated, essentially cylindrical, sleeves fixed to the surface of the rigid sheet facing the earth and extending vertically along the sheet, said sleeves being slotted along their length to allow expansion of the interior sleeve diameter and accommodate anchor pins, the anchor pins extending through each sleeve into the earth below the lower edge of the panel to anchor the lower portion of the panel against lateral displacement, and means for anchoring the upper portion of each panel against lateral displacement.
